UNITED STATES PATENT OFFICE.

JACOB H. JONES, OF ERIE, PENNSYLVANIA, ASSIGNOR TO ERIE CITY IRON WORKS, OF ERIE, PENNSYLVANIA, A CORPORATION OF PENNSYLVANIA.

FLASK-CLAMP.

No. 911,015.

Specification of Letters Patent.

Patented Jan. 26, 1909.

Application filed June 20, 1908. Serial No. 439,550.

To all whom it may concern:

Be it known that I, JACOB H. JONES, a citizen of the United States, residing at Erie, in the county of Erie and State of Pennsylvania, have invented new and useful Improvements in Flask-Clamps, of which the following is a specification.

This invention relates to flask clamps, and consists in certain improvements in the construction thereof as will be hereinafter fully described and pointed out in the claims.

The invention is particularly adapted for use with molding machines, especially that type of molding machine in which the flask is swung in the molding machine, and the pattern withdrawn by the mechanism of the molding machine. Under such conditions of use, it is very desirable to have a clamp which may be rapidly and readily applied and released, and which will assure proper clamping, and which when released will not interfere with the rapid working of the machine.

The invention is illustrated in the accompanying drawings as follows:

Figure 1 shows a bottom view of a pattern plate with the clamp in place thereon, a fragment of the molding machine being shown to show the relation of parts; Fig. 2 a side elevation of the flask, pattern plate and fragments of the molding machine to better show the relation of parts; Fig. 3 an enlarged view of the clamping jaws and connecting link; Fig. 4 a section on the line 4-4 in Fig. 1, and Fig. 5 a section on the line 5-5 in Fig. 1.

1 marks the flask; 2 the pattern plate, and 3 the bottom board.

The clamp jaw 4 engaging the bottom board is connected by the link 5 with the bell crank lever 6, the bell crank lever forming the opposing jaw of the clamp. The bell crank lever is pivoted on the lug 7 which is detachably secured to the pattern plate. One of these clamping mechanisms is arranged at each side of the flask preferably at the opposing corners as shown. Links 8 extend from the bell crank levers 6 and are secured at opposite sides of the pivot bolt of the lever 9. The lever 9 is slotted to permit of some play on the pivot bolt 11. The purpose of this floating connection is to permit of an equalization of the clamping effect at both sides of the flask, and to take up any inequalities there may be. It will be readily

seen, that each link 8 becomes a fulcrum for the opposing link, so that under ordinary conditions the pivot bolt 11 simply holds the parts in proper relation.

The pivot bolt 11 is screwed into a bar 12, which is secured to the frame pieces 13 of the molding machine. In ordinary practice, the pattern plate is also secured to the frame pieces 13 of the molding machine, and with the type of molding machine fragments of which are shown in the drawings, the frame is swung so as to turn the flask over, the flask being rammed up in the reverse position to that shown in Figs. 2 and 3. In this position the lever 9 is at the bottom of the flask, and after the ramming of the mold, the bottom board is put in place, the clamp is set from the action of the lever, and the flask swung over to the position shown in Figs. 1 and 2, the flask then resting on the part of the frame 13a.

The lever travels in a locking segment 14. This segment is made up of the upper guide bar 15 and the ratchet bar 16, and is secured to the frame pieces 13. The lever 9 has the tooth 18 which is adapted to engage the teeth 17 in the ratchet plate 16. A clip 19 is arranged over the lever, and a spring 20 is tensioned between the lever and the clip. The clip 19 is in engagement with the guide plate 15 and telescopically connected with the lever, so that the lever is yieldingly forced into engagement with the ratchet teeth through the influence of the spring 20. It will be readily seen, that as the lever is swung to put pressure on the clamp, it will be locked in said position by the mechanism just described. When it is desired to release the clamp all that is necessary is to lift the lever against the spring 20, so as to disengage it from the teeth 17. It may then be swung so as to release the clamps. It will be noted that this single lever operates a plurality of clamps at different sides of the flask.

It is desirable to have the jaws of the clamp so arranged that they will not interfere with the lifting of the pattern by the machine. In the present construction this is accomplished automatically when the lever 9 is thrown to a position to release the clamps. The jaws 4 are pivoted at 21 on the links 5, and the weighted extension 21 at the opposite side of the pivot 21 swings the jaws upwardly to the position shown in Fig. 3, 110

as soon as the clamp is released. In this position, the jaw cannot engage the bottom so that there is no danger of the interference with the action of the molding machine.

5 The jaw is shown in this open position in dotted lines at the left of Fig. 2, where the conditions above described will be observed.

It is desirable to have the clamp so arranged that it will automatically swing or 10 move out of position to interfere with the ready placing of the flask upon the pattern plate preparatory to forming the mold. The link 5 has its upper end slotted, the slot 23 engaging the pin 24 to form the connection with the bell crank lever 6. This permits of a telescopic collapsing of the link to allow it to drop out of the way. To more 15 completely accomplish this purpose I prefer to form the link 5 of pivoted sections. These 20 sections are pivotally connected by the pins 24 and 25 as shown in the drawings. When the pattern plate is reversed preparatory to receiving the flask, these pivotal connections permit the then upper part of the link to 25 swing over out of the way. The guides 26 are preferably secured to the pattern plate to maintain the part of the link nearest to the bell crank lever in position.

What I claim as new is:

- 30 1. In a flask clamp, the combination of a plurality of jaws adapted to engage and clamp a plurality of sides of a flask; and mechanism simultaneously operable by one hand of an operator for setting said jaws.
- 35 2. In a flask clamp, the combination of a plurality of jaws adapted to engage and clamp a plurality of sides of a flask; and mechanism for setting said jaws, comprising means for equalizing the pressure on said 40 jaws.
3. In a flask clamp, the combination of a plurality of jaws adapted to engage and clamp a plurality of sides of a flask; and mechanism simultaneously operable by one hand of an operator for setting said jaws and for equalizing the pressure on said jaws.
4. In a flask clamp, the combination of a plurality of jaws adapted to engage and clamp a plurality of sides of a flask; and a 50 single device for setting said jaws.
5. In a flask clamp, the combination of a plurality of jaws adapted to engage and clamp a plurality of sides of a flask; and a single lever for setting said jaws.
- 55 6. In a flask clamp, the combination of a plurality of jaws adapted to engage and clamp a plurality of sides of a flask; and a lever for setting said jaws, said lever having a floating pivotal connection for permitting 60 the equalization of pressure on the jaws.
7. In a flask clamp, the combination of a jaw; means for setting the clamp with pressure on said jaw; and means for automatically throwing the jaw out of the path of the 65 flask when the clamp is loosened.

8. In a flask clamp, the combination of a pivotally mounted jaw; means for setting the clamp by pressure on the jaw; and means for swinging the jaw out of clamping position when the clamp is released.

9. In a flask clamp, the combination of a pivotally mounted jaw; means for setting the clamp by pressure on the jaw; and a counter weight for swinging the jaw out of clamping position when the jaw is released.

10. In a flask clamp, the combination of a plurality of jaws adapted to engage and clamp a plurality of sides of a flask; means for setting said clamps by pressure on said jaws; and means for automatically throwing said jaws out of clamping position when the clamp is released.

11. In a flask clamp, the combination of a plurality of jaws adapted to engage and clamp a plurality of sides of a flask; mechanism operable by one hand of an operator for setting said clamp by pressure on said jaws; and means for throwing said jaws out of clamping position when the clamp is released.

12. In a flask clamp, the combination of a top and bottom jaw for engaging a flask; a collapsible link connecting said jaws; and means for setting said jaws.

13. In a flask clamp, the combination of a top and bottom jaw for engaging a flask; a collapsible link made up of pivotally connected sections connecting said jaws; and means for setting said jaws.

14. In a flask clamp, the combination of the top and bottom jaws; a collapsible link made up of pivotally connected sections connecting said jaws; a guide for one of the sections of the link; and means for setting the clamp by pressure on said jaws.

15. In a flask clamp, the combination of the bell crank lever forming a jaw for one side of a flask; a jaw at the opposite side of the flask; a collapsible link made up of pivotally connected sections; and means operating upon the bell crank for setting the clamp by pressure on the jaws.

16. In a flask clamp, the combination of jaws adapted to engage the top and bottom of a flask; and a telescopically collapsible link connecting said jaws.

17. In a flask clamp, the combination of a plurality of jaws adapted to engage a plurality of sides of a flask at the top and bottom; collapsible links connecting said jaws; and means for setting said jaws, said means being simultaneously operable by one hand of an operator.

18. In a flask clamp, the combination of the clamp jaws adapted to engage the top and bottom of a flask, said clamps comprising bell crank levers and an operating lever; and links connecting said bell crank levers with said operating lever at different points on the operating lever.

19. In a flask clamp, the combination of the clamp jaws adapted to engage the top and bottom of a flask, said clamp comprising bell crank levers, and an operating lever; and a floating pivotal mounting for the operating lever between the link connections.

20. In a flask clamp, the combination of clamp jaws adapted to engage the top and bottom of a flask, said clamps comprising bell crank levers and an operating lever; and means for locking the operating lever.

21. In a flask clamp, the combination of the clamp jaws adapted to engage the top and bottom of a flask, said clamps comprising bell crank levers, and an operating lever; a ratchet segment; and devices on the operating lever for engaging the segment.

22. In a flask clamp, the combination of the clamp jaw adapted to engage the top and bottom of a flask, said clamp comprising bell crank levers and an operating lever; a ratchet segment; a tooth 18 on the lever for engaging the segment; the clamp 19 telescopically mounted on the lever; the spring 20 between the clip and lever; and a guide 25 plate 15 for holding the clip in position.

In testimony whereof I have hereunto set my hand in the presence of two subscribing witnesses.

JACOB H. JONES.
